(57) CLAIM

The ornamental design for an arms and chest exerciser, as shown.

DESCRIPTION

The intended application of this invention is to strengthen and/or tone the muscles of the arms and chest.

FIG. 1 is a front elevational view of an arms and chest exerciser showing my new design;

FIG. 2 is a left side elevational view thereof;

FIG. 3 is a top plan view thereof;

FIG. 4 is a right side elevational view thereof; and,

FIG. 5 is a bottom plan view thereof.

The rear elevational view is a mirror image of the front elevational view.
